UNITED STATES PATENT OFFICE.

ALFRED GIVEN, OF ELLENSBURG, WASHINGTON.

LOCOMOTIVE.

SPECIFICATION forming part of Letters Patent No. 633,831, dated September 26, 1899.

Application filed August 2, 1898. Serial No. 687,522. (No model.)

To all whom it may concern:

Be it known that I, ALFRED GIVEN, of Ellensburg, in the county of Kittitas and State of Washington, have invented a new and Improved Locomotive, of which the following is a full, clear, and exact description.

The invention consists of novel features and parts and combinations of the same, as will be fully described hereinafter and then pointed out in the claim.

Reference is to be had to the accompanying drawings, forming a part of this specification, in which similar characters of reference indicate corresponding parts in all the figures.

Figure 1 is a side elevation of the invention. Fig. 2 is a plan view of the same with the boiler omitted. Fig. 3 is an enlarged transverse section of the improvement substantially on the line 3 3 in Fig. 1, and Fig. 4 is a sectional side elevation of the same on the line 4 4 in Fig. 3.

The rotary engine is provided with a cylinder A, in which is mounted to rotate a piston B, having two piston-heads B' B², formed with buckets B³ B⁴, extending in opposite directions, one piston-head being used for driving the engine forward and the other for reversing purposes, as hereinafter more fully described. The cylinder A when used on a locomotive is mounted transversely on the front truck in the usual manner, and the shaft C of the piston carries on its outer ends crank-disks D D', connected by pitmen E E' with the drivers F F' of the locomotive.

When the steam acts on the buckets B³ of the head B', then the rotary motion given to the piston causes a forward movement of the locomotive owing to the connection with the drivers, as above described; but when the steam acts on the buckets B⁴ of the other piston-head then the piston rotates in an opposite direction and the locomotive backs up.

The cylinder A is provided with two steam-inlet ports a, leading to the interior of the cylinder into cavities b, arranged segmentally on the inside of the cylinder at or about the middle of the two piston-heads B' B², as plainly indicated in the drawings. The outer ends of the said ports a are connected with inlet-pipes G G', extending into a smoke-box H, and either of said pipes is adapted to be connected by a valve G² with a steam-supply pipe G³, extend-

ing into a dome I, said pipe containing the usual throttle-valve for regulating the amount of steam passing from the dome into the pipe G³. The cylinder A is also provided with two exhaust-ports c for carrying the exhaust-steam from the cylinder-heads B' B² to exhaust-pipes J J', containing a valve K and extending in the smoke-box H, as is plainly indicated in the drawings. The valve K has a stem K' extending through the smoke-box to the outside to carry at its outer end an arm K², connected by a link K³ with the interior of the cab, so that the engineer can manipulate the valve K so as to open or close either of the pipes J or J' by turning the said valve accordingly. The valve G² is similarly operated by the engineer from the cab, and for this purpose the stem G⁵ of the valve is provided at its outer end with an arm G⁴, connected by a link G⁶ with the cab to permit the engineer to shift the valve G² so as to connect the supply-pipe G³ with either of the pipes G or G'.

When the several parts are in the position illustrated in the drawings, the pipe G³ is connected by the valve G² with the pipe G, so that live steam can pass from the boiler into the cylinder A to act on the buckets B³ of the cylinder-head B' to turn the piston B for propelling the locomotive forward. The exhaust-pipe J, leading from the cylinder to the head B', is now opened, while the other pipe J' is closed, so that no exhaust-steam can pass from the smoke-box down the pipe J' to act on the buckets B⁴ of the head B², while at the same time a free escape is provided for the exhaust-steam from that part of the cylinder containing the head B'.

When it is desired to reverse the engine, the engineer turns the valve G² and then the valve K, so as to connect the supply-pipe G³ with the pipe G' and to cut off the pipe G from the steam-supply. The valve K closes the pipe J and opens the pipe J' to form an exhaust for the cylinder A at the piston-head B². The live steam working on the buckets B⁴ of the piston-head B² reverses the motion of the piston, and consequently that of the drivers, so as to back up the locomotive. The exhaust-steam from the pipe J' cannot enter the pipe J, as the latter is closed, and hence there is no back pressure possible in the cylinder A at the piston-head B'.

The cavities *b* extend a sufficient distance around in the cylinder to supply one, two, or more buckets with the motive agent. The piston is suitably packed to avoid leakage of 5 the motive agent.

Having thus fully described my invention, I claim as new and desire to secure by Letters Patent—

In a locomotive, the combination with the 10 smoke-box and truck thereof, of a rotary engine-cylinder mounted on the truck beneath the smoke-box, pistons working in the cylinder, connections between the pistons and the driving-wheels of the locomotive, the upper 15 portion of the cylinder being extended to the smoke-box and such portion of the cylinder having two sets of feed and exhaust ports.

respectively for the pistons, a pipe leading to each feed-port, the pipes being joined to each other to form a valve-seat and communicating with the steam-supply at such point, a valve working in the valve-seat, connections between the valve and the locomotive-cab, two exhaust-pipes respectively for the exhaust-ports, the exhaust-pipes being joined to each other to form a valve-seat, a valve mounted in the valve-seat of the exhaust-pipes and commanding the same, and connections between the exhaust-valve and the locomotive-cab.

ALFRED GIVEN.
